United States Patent Office

Des. 211,006
Patented May 14, 1968

211,006

BOTTLE

Stephen J. Kneapler, Miami, Fla., assignor to Richford Corporation, Farmingdale, N.Y., a corporation of New York

Filed July 17, 1967, Ser. No. 7,838

Term of patent 14 years

(Cl. D9—143)

FIG. 1

FIG. 2.

FIG. 3

FIG. 4

FIG. 1 is a front elevational view of a bottle embodying my new design;

FIG. 2 is a side elevational view thereof;

FIG. 3 is a bottom plan view thereof; and

FIG. 4 is a top plan view thereof.

The dominant features of my new design are shown in solid lines in the drawing.

I claim:

The ornamental design for a bottle, substantially as shown and described.
